UNITED STATES PATENT OFFICE.

JOHN C. EDWARDS, OF UTICA, NEW YORK.

LATCH-LEVER LOCK.

Application filed May 1, 1924. Serial No. 710,285.

To all whom it may concern:

Be it known that I, JOHN C. EDWARDS, a citizen of the United States of America, of Utica, in the county of Oneida, in the 5 State of New York, have invented new and useful Improvements in Latch-Lever Locks, of which the following, taken in connection with the accompanying drawings, is a full, clear, and exact description.

10 This invention relates to electric locking devices for railway switch and signal operating levers which are usually assembled in battery relation upon a suitable supporting bed within a relatively small area and preferably within a tower or other protective 15 housing along the railway within practicable distances from the switches or signals to be operated.

One of the objects is to provide a simple, 20 compact and efficient locking means for levers of this character so that a battery of similar levers equipped with the locks may be installed in a smaller area than has heretofore been practiced without in any 25 way interfering with the free operation of each lever and its locking means independently of the others.

These levers are usually provided with a 30 latch rod adapted to be operated at will to cooperate with the usual rocker arm and other suitable mechanism for retaining the lever in its adjusted position, and another object of this invention is to establish an 35 electrically controlled locking connection between the lever and latch rod whereby a slight endwise movement of the latch rod relatively to the lever will automatically 40 release the lock and permit the latch rod and lever to perform their usual functions in releasing, adjusting and setting the railway switches or signals.

Another object is to provide the locking 45 segment and locking bolt with cooperative means for positively restoring the bolt to its locking position for locking the latch rod when the latter is returned by its retracting spring.

One of the specific objects is to connect 50 an electric switch in the lock magnet circuit and to close the switch by slight initial operation of the latch rod against the action of its retracting spring for energizing the magnet and withdrawing the locking bolt from its locking position immediately preceding the shifting of the lever.

Other objects and uses relating to specific parts of the lock operating and releasing device will be brought out in the following description.

In the drawings:

Figure 1 is a side elevation of a reversely operating lever and my improved latch lock mounted thereon.

Figure 2 is an enlarged side elevation of the lock operating and releasing mechanism with the cover removed showing the adjacent portions of the lever and latch rod.

Figure 3 is a vertical sectional view taken in the plane of line 3—3, Figure 2, with the lock cover in place.

Figures 4, 5 and 6 are detail sectional views taken respectively in the planes of lines 4—4, 5—5 and 6—6, Figure 2.

This locking, operating and releasing mechanism is adapted to be used in connection with any of the standard forms of railway switch and signal operating levers as 75 —1— having a latch rod —2— mounted thereon for use in connection with any of the well-known forms of devices for retaining the lever in its adjusted position, said lever being pivoted at —3— to any suitable supporting base and provided with reversely extending arms —4— for connection with the railway switches or signals not shown.

The latch rod —2— is slidable lengthwise of and in proximity to one edge of the lever —1— and is guided in its vertical movement in bearings —5— of a bracket —6— which is secured to said lever in proximity to but a relatively short distance below the locking device, said latch rod being extended beyond the lower and upper bearings —5— and has its lower end provided with a shoulder —7— for connection with any 90 suitable means for holding the lever in its adjusted position while the upper end of the rod is pivotally connected at —8— to an operating handle —9— which in turn is pivoted at —10— to the lever —1— some distance above the lock presently described, whereby inward rocking movement of the

95 free end of the handle toward the lever will draw the rod upwardly against the action of a retracting spring —11—.

A split clamp —12— is slidably adjustable lengthwise of and upon the latch rod —2— and is held in its adjusted position by clamping bolts —13— which pass through registering apertures in the clamp —12—.

and latch rod —2—, said clamp being provided with a radially projecting locking pin —14—.

5 A lock-supporting frame —15— is secured by clamping bolts —16— to one side of the lever —1— to extend some distance above and below the locking pin —14— and is provided with a removable box-shaped cover —17— which is held in place by a key lock —18— thereon, adapted to engage a keeper —19— on the frame —15— to cooperate with said frame in forming a protective housing for the inclosed locking mechanism.

15 A vertically oscillatory locking segment or keeper —20— is journaled upon a supporting stud —21— on the frame —15— and is provided at one side of the stud —21— with a radially extending arm —22— having an elongated slot —23— for receiving 20 the pin —14— and establishing an operative connection between the latch rod —2— and segment —20— whereby endwise vertical movement of the latch rod will impart a corresponding rocking movement to the 25 segment for purposes presently described.

An iron armored solenoid —24— is supported directly over the segment —20— by a pair of vertically spaced bracket rings —25— on the frame —15— and preferably 30 cast integral therewith so as to embrace the lower and upper ends of the solenoid and support the same in a vertical position, the ring —25— being connected by a central connecting bar —25'—, Figure 2.

35 The solenoid is provided with a vertically movable coaxial plunger —26— extending downwardly therefrom and guided in an apertured lug —27— on the frame —15—, said lug being provided with a movable section —27'— held in place by screws —28— to permit access of the plunger for removal and replacement when desired and also to take up wear.

40 The lower end of the plunger is recessed to form a shoulder —29— which is movable into and out of a peripheral notch —30— in the upper edge of the segment —20—, said edge being preferably concentric with the axis of the stud —21— and is adapted to 45 travel in close proximity to the lower similarly curved face of the guide lug —27— as the segment —20— is rocked vertically.

50 The intermediate portion of the segment —20— between the stud —21— and notch —30— is provided with an opening —31— for receiving a radially projecting pin —32— on the lower end of the plunger —26—, the upper wall of a portion of the opening —31— being provided with an inclined cam face —33— for engaging said pin —32— and restoring the plunger —26— to its locking position in the notch —30— when the arm —22— of the segment is 55 rocked downwardly by a corresponding movement of the latch rod —2—.

The upper portion of the segment —20— having the notch —30—, overlaps upon the recessed portion of the plunger —26— between the shoulder —29— and pin —32— so as to travel in the recess and to assist in 70 guiding the plunger and segment in their relative movements.

The peripheral length of the notch —30— is slightly greater than the corresponding width or diameter of the adjacent portion 75 of the plunger —26— to permit a limited vertical rocking movement of the segment relatively to the plunger when the latter is in its locking position in the recess —30— for a purpose presently described.

80 A horizontal rock shaft —34— is journaled in transversely spaced bearings —35— on the frame —15— and on this rock shaft between the bearings —35— is secured a circuit-controlling drum —36— of insulating material carrying an annular conducting ring —38— and a segmental conducting ring —38'— both of which latter are secured to the periphery of the drum —36— in axially spaced relation and therefore, 85 insulated from each other.

90 An insulating block —37— is secured by screws to the inner face of the frame —15— between the bearings —35— to extend some distance above and below the insulator drum —36— but in spaced relation thereto and upon this insulating block are mounted 95 separate pairs of contact brushes —39— and —39'—, the brushes —39— being secured by binding posts —40— to the insulating block —37— to engage diametrically opposite sides of the contact ring while the brushes —39'— are secured by binding posts —40'— to the same insulating block in spaced relation to the binding posts —40— to engage 100 diametrically opposite sides of the segmental contact ring —38'—.

105 The ends of the segmental ring —38'— are spaced apart leaving an intervening portion of the insulating drum —36— exposed 110 for contact with one of the brushes —39'— while the other brush —39— remains in contact with the segmental ring —38'— as shown in Figures 2 and 3.

115 Mounted upon the insulating block —37— is a pair of terminals —41— for receiving lead wires —42— and —42'— from any available source of electric energy through the medium of a normally opening switch not shown but adapted to be closed by the operator to permit unlocking of the latch lever in the manner described.

120 One of the binding posts —41— is electrically connected by a wire —44— to one of the binding posts —40— of the adjacent brush —39—, the other binding post —40'— and its corresponding brush —39— being connected by a wire —44'— to one end of the winding of the solenoid —24—.

125 The other terminal —41— is electrically 130

connected to the adjacent binding post $-40'$ and its contact brush $-39'$ while the other binding post $-40'$ and corresponding brush of the segmental ring $-38'$ is connected by a wire -45 to the other end of the winding of the solenoid -24 . The locking segment -20 and rock shaft -34 extend in the same general direction transversely of the axis of the stud -21 in planes one above the other, the segment being connected to the latch rod -2 at one side of its axis while at the opposite side of said axis is located a link -48 having its upper end connected by a ball and socket joint -49 to the corresponding end of the segment and its lower end connected by a ball and socket joint -50 to a crank arm -51 on the adjacent end of the rock shaft -34 whereby rocking motion is imparted to the shaft -34 and its drum -36 as the segment -20 is rocked vertically about its axis by the endwise movement of the latch rod -2 .

When the latch rod -2 is forced to its extreme down position by its retracting spring -11 , the rock shaft -34 and its insulating drum -36 will be adjusted to withdraw the contact ring $-38'$ out of contact with the upper brush $-39'$ and in contact with the adjacent portion of the insulated drum while the lower contact brush $-39'$ will remain in contact with the segmental ring at which time, the shoulder -29 of the plunger constituting a locking dog, will be in interlocking engagement with the notch -30 of the segment -20 , but as previously stated, the peripheral length of the notch -30 is somewhat greater than the corresponding width of the dog -29 which allows a limited upward movement of the latch rod -2 before engaging the rear wall of the notch -30 with the dog -29 thereby effecting a corresponding rocking movement of the shaft -34 and its drum -36 sufficient to bring the contact ring $-38'$ into electrical contact with the upper brush $-39'$ thereby closing the circuit through and, after current is made available in the wires -42 and $-42'$ energizing the solenoid winding and causing an upward movement of its plunger -26 sufficient to withdraw the dog -29 from the notch -30 and to allow the further closing of the latch rod -2 for releasing the latch not shown, connected thereto, which permits the free operation of the lever -1 for effecting the desired operation of a switch or signal through the medium of their connections either with one or both of the arms -4 .

When the lever is adjusted to the proper position, the latch rod -2 is released to restore the latch and hold the lever in such position, thereby restoring the insulating

drum -36 and its contact rings -38 and $-38'$ to their normal positions for de-energizing the magnet and allowing the plunger to be positively returned to its normal down position by the engagement of the cam -33 with the pin -32 .

The direct connection between the segment -20 and latch rod -22 through the medium of the pin -14 and clamp -12 together with the direct engagement of the locking dog -29 on the plunger -26 with the notch -30 in the periphery of the segment and the positive action of the cam -33 on the pin -32 for returning the plunger to its normal position, enables the various parts of the lock to be assembled in compact relation upon the lever -1 which allows a larger number of the levers to be installed in battery relation in a more compact space than has heretofore, been practicable.

Furthermore, the specific locking connections between the solenoid, plunger and segment and between the segment and latch rod assures a more reliable locking means to prevent accidental release of the latch when the lever is set to the desired position thereby increasing the safety factor of signal and switch operating levers of this character.

This safety factor is further increased by the use of the commutator drum -36 carrying contact rings -38 and $-38'$ for cooperation with their respective sets of brushes -39 and $-39'$ together with the connection between the segment -20 and commutator shaft whereby the release of the lock is made dependent upon the energizing of the solenoid which can only be effected by the rotation of the commutator drum -36 , sufficient to bring the ring $-38'$ into contact with the upper brush $-39'$.

It will also be noted that this movement of the commutator drum is made dependent upon the initial upward movement of the latch rod -2 by means of its handle -9 which assures the retention of the latch in its holding position and consequent holding of the lever in its adjusted position until the latch rod is operated by an authorized operator.

This control of the locking device through the medium of the latch rod -2 and handle -9 also simplifies the construction of the lock as a whole and greatly facilitates the control of the lock.

Although I have shown and described means mounted on the lever and operatively connected directly to and actuated by the latch rod by a limited movement of the latch rod for bringing into action means for tripping the detent as -26 , it is evident that other means such as a floor switch or equivalent device might be directly connected to the electro-magnet -24 for tripping said detent.

I claim:

1. The combination with a latch lever and a latch operating member movable relatively thereto, of means for locking said member against movement to its latch-releasing position, and electrically operated means brought into action by a limited movement of said member toward its latch-releasing position for releasing the locking means when current is available in the electrically operated means.

2. The combination with a latch lever and latch operating rod movable endwise of and upon said lever, of means for locking said rod against movement to its latch-releasing position, and electrically operated means brought into action by a limited movement of said rod toward its latch-releasing position for releasing said locking means when current is available in the electrically operated means.

3. The combination with a latch lever and a latch operating member movable relatively thereto, and having a limited movement without releasing the latch, of means for temporarily locking said member against movement beyond said limit, and electrically operated means brought into action by said limited movement for releasing the locking means and permitting said member to be moved to its latch-releasing position when current is available in the electrically operated means.

4. The combination with a latch lever and latch operating member movable relatively thereto and having a limited movement without releasing the latch, of a rocking member operatively connected to and actuated by said latch-releasing member, means for temporarily locking said rocking member against movement beyond said limit, and electrically operated means brought into action by the limited movement of the rocking member for releasing the locking means when current is available in the electrically operated means.

5. A latch-lever locking device comprising in combination with a hand lever and a latch operating member, means for locking said member against movement to its latch-releasing position including a rocker arm carried by the lever and operatively connected directly to the latch releasing member, a detent for the rocker-arm, said rocker-arm having a limited movement relatively to the detent, and electrically operated means brought into action by said limited movement for tripping the detent when current is available in the electrically operated means.

6. In a latch-lever lock, the combination with a lever and a latch operating rod, of a movable member carried by the lever and directly connected to the rod to be operated thereby, a detent for said member, and elec-

trically operated means brought into action by an initial movement of said member for tripping the detent when current is available in the electrically operated means.

7. In a latch-lever lock, the combination with a lever and a latch operating rod, a pin operatively mounted on the rod, a movable member mounted on the lever and actuated by said pin as the latch rod is operated toward its latch-releasing position, a detent for said member, and electrically operated means in the lever actuated by said member for tripping the detent when current is available in the electrically operated means.

8. In a latch lever lock of the character described, an electric lock and a keeper therefor, both mounted upon the lever, said keeper being operatively connected to and actuated by the latch and having a slight movement independently of the lock, and means actuated by the independent movement of said keeper for energizing the lock and releasing the keeper when current is available in the electric lock circuit.

9. In a latch lever lock of the character described, the combination with a lever and a latch rod movable relatively thereto, a movable member on the lever operatively connected directly to and actuated by said rod, a detent for holding said member and rod against movement to the latch releasing position, and electrically operated means for tripping the detent when current is available in the electrically operated means.

10. In a latch lever lock of the character described, an electric lock and a keeper therefor, both mounted upon the lever, said lock and keeper being provided respectively with a locking bolt and a notch for receiving the bolt, the notch being of slightly greater width than the corresponding width of the bolt to permit slight movement of the keeper relatively to the bolt, means for transmitting motion from the latch to the keeper for moving the latter relatively to the detent, and means actuated by the keeper for closing the circuit through the electric lock and thereby actuating the detent to release the keeper when current is available in the lock circuit.

11. In a latch lever lock, a keeper pivoted to the lever and operatively connected to the latch to be actuated thereby, a locking member adapted to be engaged by the keeper for limiting the movement of said keeper and latch operated thereby, said latch and keeper having a slight movement relatively to the locking member while the latter is in its locking position, and means brought into action by the slight movement of the keeper for causing the withdrawal of the locking member from the keeper.

12. In a latch lever lock of the character described, a keeper pivoted to the lever and

operatively connected to the latch to be actuated thereby, said keeper having a peripheral notch, a locking bolt normally engaging in the notch for limiting the movement of the keeper, said notch being of sufficient width to allow a limited movement of the keeper relatively to the bolt when the latter is in its locking position, means actuated by said limited movement of the keeper for

10 withdrawing the locking bolt from its locking position, and cooperative means on the keeper and locking bolt respectively for returning the locking bolt to its locking position when the keeper and latch are returned to their starting positions.

15 In witness whereof I have hereunto set my hand this 15th day of April, 1924.

JOHN C. EDWARDS.
